UNITED STATES PATENT OFFICE.

ELLSWORTH A. HAWTHORNE, OF BRIDGEPORT, CONNECTICUT.

LAMP-MOUNTING.

1,090,981.

Specification of Letters Patent. Patented Mar. 24, 1914.

Application filed March 24, 1913. Serial No. 756,492.

To all whom it may concern:

Be it known that I, ELLSWORTH A. HAWTHORNE, a citizen of the United States, and a resident of Bridgeport, county of Fairfield, and State of Connecticut, have invented an Improvement in Lamp-Mountings, of which the following description, in connection with the accompanying drawings, is a specification, like characters on the drawings representing like parts.

This invention relates to lamp mountings, and more especially to a universally adjustable mounting, or bracket, for supporting a lamp upon the steering structure of a cycle.

My invention will be best understood by reference to the following specification, when taken in connection with the accompanying drawings of several specific embodiments thereof, while its scope will be more particularly pointed out in the appended claims.

In the drawings: Figure 1 is a plan of one form of lamp mounting embodying my invention; Fig. 2 is a side elevation of the same; Fig. 3 is a front elevation of the same; Fig. 4 is an enlarged detail side elevation, partly in section, of a modification in which the lamp mounting is secured to the handle bar only; Fig. 5 is an elevation of the parts shown in Fig. 4, viewed from the right side; Fig. 6 is a side elevation of another form of mounting, in which an acetylene gas generator for the lamp is also mounted on the lamp mounting; Fig. 7 is a side elevation of the mounting shown in Fig. 6, as adapted for a battery to supply current to an electric lamp mounted on the mounting; Fig. 8 is a side elevation of still another mounting adapted for an acetylene gas tank at the rear of the lamp; Fig. 9 is a side elevation of the mounting shown in Fig. 8, adapted to support the battery for supplying current to the lamp; and Fig. 10 is a side elevation of another form of lamp mounting embodying my invention, in which the brace rods extend from the lamp supporting arms downwardly to the front axle of the cycle.

Referring to the drawings, and more especially to Figs. 1, 2 and 3, 11 is a lamp, which may be of any suitable type, which it is desired to support on the steering structure of a cycle. The latter comprises a fixed head 12, and a swiveled steering head 13, having a usual handle bar 14 and a pair

of fork braces 15—15 of common form, 55 which serve in the case of a motor cycle to brace the front fork. These fork braces are usually inclined forwardly and downwardly from their point of attachment to the steering head, and in some cases diverge 60 downwardly, while in other cases, they are parallel.

In the construction shown in Figs. 1, 2 and 3, the fork braces 15—15 serve as supports for a pair of lamp-supporting arms 16—16, the latter being provided with vertical studs 17—17 passing upwardly through and secured to lugs 18—18 of the lamp, by means of nuts 19—19. In order to provide for the angular adjustment of the lamp in a vertical plane, as well as to provide for an adjustment of its mounting to suit supports of different dimensions, the lamp supporting arms 16 are mounted on the supports 15 by suitable universal connections and 75 suitable clamps. Any other suitably adjustable connections may be provided, but herein each of the arms 16 is mounted on a pivot 20 on substantially horizontal axes A—A, so as to permit the lamp to be angularly adjusted 80 in a vertical plane. The pivots 20, in turn, are mounted on swivel members 21, which latter are swiveled on pairs of suitable clamps 22 secured to the supports 15. Each pivot 20 may be in form of a bolt passing 85 through the arm 16, and swivel member 21, and if desired, the latter may be provided with suitable means interengaging with the arm to lock the latter in the desired position of adjustment. Such locking means 90 may be in the form of two sets of interengaging teeth 23 and 24 (see Fig. 3), which may be disengaged by simply loosening the bolt, then adjusted to the proper angle, and afterward locked in the new position of adjustment by tightening up the bolt in an obvious manner. The swivel members 21 are mounted on the clamps 22 to turn about axes B—B, preferably at right angles to the axes A—A of the pivots 20. By this means, 100 the arms 16 may be adjusted not only about the axes A—A of the pivots 20, but also about the axes B—B of the swivels 21. As a means for securing the swivels 21 to the clamps 22 and securing the latter to the supports 15, the swivels may be provided with screw-threaded shanks 25 passing through the clamps, and provided with nuts 26.

Each of the clamps 22 is herein composed of two clamp members 27 and 28, the latter being provided with one or more slots 29 adapted to receive tongues 30 provided on 5 the clamping members 27, respectively. By this means, the clamp 22 may be adjusted to fit the supports 15 of various diameters within their range of adjustment, and said clamps may be adjusted about the axes C—C 10 of said supports. As a further means for securing the lamp supporting arms 16 in the selected position of adjustment, and bracing said arms to prevent the lamp from vibrating, I may employ braces extending from 15 said arms to some suitable part of the supporting structure. In the form shown in Figs. 1, 2 and 3, I have shown a pair of braces 31 extending from the forward end of the lamp supporting arms 16 to the 20 handle bar 14. As a means for securing each of the braces 31 to its respective lamp supporting arm 16, a clamping collar 32 encircling the forward end of such arm is provided with a pair of ears 33 embracing the 25 forward end of the brace rod, and provided with a clamping screw 34, which latter also serves as a pivot about which the brace rod may be swung in a vertical plane. It will now be understood that the brace rods 31 30 may be adjusted about the vertical axes D—D of the forward ends of the lamp supporting arms, and about the horizontal axes E—E of the pivots 34. It will be evident, also, that the lamp supporting arms may be 35 adjusted about the axes D—D, by swiveling the studs 17 in the lugs 18.

The rear ends of the brace rods 31 are herein secured to the handle bar 14, by means of clamps 35 encircling and clamp- 40 ing about the latter, each of these clamps in the present instance comprising two clamp members 36 and 37 provided respectively with ears 38 and 39. Each brace rod, where it passes through the ears 38 and 39 of its 45 respective clamp, is screw-threaded and provided with clamping nuts 40 and 41, which may serve the double purpose of contracting the clamp and adjusting the brace rod longitudinally. Since handle bars vary some- 50 what in diameter, the clamps 35 are preferably provided with means permitting a considerable range of adjustment. In the present instance, the clamp member 37 is provided with a plurality of slots 42, either 55 of which is adapted to receive a tongue 43 provided on the clamp member 36. The nuts 40 and 41 obviously serve as an additional means of adjustment, as well as serving to contract the clamps about the handle 60 bar 14 to secure them rigidly in place. It will now be evident that since the clamps 35 are swiveled on the handle bar 14, they provide a means for permitting adjustment of the brace rods 31 about axes F—F, while 65 the brace rods are being adjusted about axes

E—E. If desired, the brace rods 31 may be made longitudinally adjustable or extensible, by means of sleeve nuts or turnbuckles 44, interposed between, and having right and left screw-threaded engagement with, the front 70 and rear parts of the brace rods.

If desired, the lamp mounting may also serve as a mounting for the number-plate required by law in some States to be carried on the front part of the machine. This 75 may be accomplished very conveniently by providing a pair of uprights 45, having their lower terminal portions bent to conform to the shape of the clamp member 37, and provided with suitable perforations to 80 receive the brace rods 31, while the nuts 41 serve to rigidly clamp the uprights in place, thereby forming an effective and attractive means for supporting a number-plate 46 secured to the uprights. In some cases, it 85 may be desirable to support the lamp-supporting arms upon the handle bar of the cycle, as shown in Figs. 4 and 5. In such case, no changes in the construction of the mounting hereinbefore described will be 90 necessary, except the omission of the brace rods, which in the described construction extend from the handle bar to the forward ends of the lamp-supporting arms. In the construction shown in Figs. 4 and 5, how- 95 ever, I have shown a slight modification of the clamp for securing the swivels to the handle bar. In this form, the clamp comprises two clamp members 47 and 48, which instead of being provided respectively with 100 interlocking tongues and slots, as in the already described form, are provided with ears 49 and 50 to receive the clamping bolt 51. In other respects, the mounting is ex- 105 actly similar to that illustrated in Figs. 1, 2 and 3.

If desired, the lamp mounting may also serve as a convenient mounting for an appropriate lamp supply means, as illustrated in Figs. 6, 7, 8 and 9. In cases where an 110 acetylene gas lamp is employed in connection with the generator, the latter may be conveniently supported at the rear of the lamp upon the lamp mounting, as illustrated in Fig. 6. This may be accomplished by 115 simply dispensing with the described turn- 120 buckles or sleeve nuts 44, and mounting a gas generator 52 on the brace rods by means of appropriate clamps 53. If an electric lamp is employed, the brace rods 31 may 125 serve as a support for a lamp supply means in the form of a suitable battery, or batteries, mounted in a case 54, supported on the brace rods, as shown in Fig. 7, directly at the rear of the lamp.

In case it is desired to employ a gas storage tank to supply the lamp, I may substitute for the brace rods 31 a pair of brace rods 55, as shown in Fig. 8, appropriately formed to receive the tank, the latter being 130

securely held in place by means of suitable straps 56, partially encircling the tank, and secured to the brace rods by bolts 57. In other respects, the lamp mounting may be exactly similar to that already described, and shown in Figs. 1, 2 and 3. By simply omitting the straps 56, the bolts 57 may serve as a convenient means for mounting a battery, or battery box 58 on the brace rods 55, as illustrated in Fig. 9, without requiring other change in the construction of the mounting. By supporting the lamp supply means upon the lamp mounting in any of the described ways, a short direct connection with the lamp can be made, and the use of long, inconvenient, flexible connections may be avoided, thus obviating the objection which has heretofore existed, where the lamp supply means was located on the main frame of the cycle. By placing the lamp supply section directly upon the lamp mounting, moreover, it is out of the way of the rider, and may be easily controlled by providing a controlling valve or switch, as the case may be, adjacent the handle bar; so that the lamp may be conveniently regulated.

Referring now to Fig. 10, this form of my invention is similar in all respects to that shown and described in connection with Figs. 1, 2 and 3, with the exception that I have substituted for the brace rods 31 and their connections a pair of brace rods 59, extending from the lamp supporting arms to the axle 60 of the cycle, the lower terminal portions of these brace rods being provided for this purpose with ears 61, through which the usual axle 60 extends. If desired, these brace rods may be made longitudinally adjustable or extensible, by means of sleeve nuts or turnbuckles 62 having screw-threaded engagement with upper and lower sections of the brace rods, as clearly shown in Fig. 10. By this means, the angle of inclination of the lamp may be readily adjustable, and the lamp rigidly held in fixed position while in use.

While I have herein shown and described several embodiments of my invention for illustrative purposes, and have discussed and disclosed in detail the construction and arrangement incidental to several applications thereof, it is to be understood that the invention is limited neither to the mere details nor relative arrangement of parts, nor to its specific embodiments herein shown, but that extensive deviations from the illustrated forms or embodiments of the invention may be made without departing from the principles thereof.

Having thus described my invention, what I claim and desire by Letters Patent to procure is:—

1. The combination with a lamp and a suitable support, of a pair of lamp-support-

ing arms extending in general direction horizontally and pivotally mounted on said support to permit said lamp to be adjusted in a vertical plane, and means connected to the outer ends of said arms rigidly to hold said arms in the selected position of adjustment. 70

2. The combination with a lamp and a suitable support, of a rigid mounting comprising a pair of lamp-supporting arms extending laterally from said support and pivotally mounted on said support to permit said lamp to be adjusted in a vertical plane, and brace means also extending laterally from said support to hold said arms rigidly in the selected position of adjustment. 75

3. The combination with a lamp and a suitable support, of a rigid mounting comprising a pair of lamp-supporting arms extending laterally from said support and pivotally mounted on said support to permit said lamp to be adjusted in a vertical plane, and a pair of brace members also extending laterally from said support and rigidly connecting said arms to said support. 80

4. The combination with a lamp, of a rigid mounting therefor comprising pivoted lamp-supporting means extending in general direction horizontally and permitting vertical adjustment of said lamp, and brace means also extending in general direction 95 horizontally to hold said lamp rigidly in the selected position of adjustment. 90

5. The combination with a lamp, of a rigid mounting therefor comprising pivoted lamp-supporting means permitting vertical 100 adjustment of said lamp, brace means to hold said lamp rigidly in the selected position of adjustment, lamp-supply means mounted on said brace means, and means upon which said mounting as a whole is 105 mounted to swing laterally thereby to carry said lamp and said supply means as a unitary structure.

6. The combination with the steering structure of a cycle, of a lamp, and a rigid 110 mounting for said lamp comprising lamp-supporting means extending forwardly from said steering structure, and brace means rigidly connecting said steering structure to the forward portion of said lamp-supporting 115 means.

7. The combination with the steering structure of a cycle, of a lamp, and a rigid lamp mounting comprising a pair of lamp-supporting arms pivotally mounted on said steering structure to swing in substantially parallel vertical planes and secured to opposite sides of said lamp, and means to secure said arms in fixed position. 120

8. The combination with the handle bar 125 and steering head of a cycle, of a lamp, and a rigid lamp mounting comprising lamp-supporting means extending forwardly and upwardly from said steering head, and brace means extending from said handle bar to the 130

forward portion of said lamp-supporting means, and rigidly connecting said lamp-supporting means to said handle bar.

9. The combination with the handle bar 5 and steering head of a cycle, of a lamp, and a rigid lamp mounting comprising lamp-supporting means extending forwardly and upwardly from said steering head, and adjustable brace means extending from said 10 handle bar to the forward portion of said lamp-supporting means, and rigidly connecting said lamp-supporting means to said handle bar.

10. The combination with the handle bar 15 and steering head of a cycle, of a lamp, a rigid lamp mounting comprising lamp-supporting means extending forwardly and upwardly from said steering head, brace means extending from said handle bar to the forward portion of said lamp-supporting means and rigidly connecting said lamp-supporting means to said handle bar, and lamp supply means supported on said brace means.

11. The combination with a lamp, of a 25 rigid lamp mounting comprising a pair of arms extending in general direction horizontally and supporting said lamp, means on which said arms are swiveled permitting angular adjustment of said arms toward or from each other and angular adjustment of the lamp in a vertical plane, and means positively to lock said arms in the selected position of adjustment.

12. The combination with a lamp, of a 35 pair of upwardly rising laterally diverging arms, means on which said arms are swiveled to permit angular adjustment of said arms toward or from each other and angular adjustment of said lamp in a vertical plane, 40 and means to lock said arms in the selected position of adjustment.

13. A lamp mounting comprising, in combination, a pair of independent lamp supporting arms, a pair of supports, and independent universal connections between said arms and said supports.

14. A lamp mounting comprising, in combination, a pair of lamp-supporting arms, a pair of supports, a pair of clamps secured to 50 said supports, and means adjustable to secure said arms to said clamps.

15. A lamp mounting comprising, in combination, a pair of independent lamp-supporting arms, a pair of spaced supports, 55 means connecting one of said arms to its support permitting such arm to be adjusted about either of two axes, and other means

connecting the other of said arms to said support permitting said arms to be adjusted about either of two axes.

16. A lamp mounting comprising, in combination, a pair of independent lamp-supporting arms, a pair of spaced supports, means for securing one of said arms to its support including two swivel members 65 whose axes are transverse to each other, and other means for securing the other of said arms to its support including two swivel members whose axes are transverse to each other.

17. A lamp mounting comprising, in combination, a pair of lamp-supporting arms, a pair of swivel members, on which said arms are adjustably pivoted, a pair of supports on which said swivel members are adjustably 75 pivoted, and means to secure said arms and said swivel members in the desired position of adjustment.

18. A lamp mounting comprising, in combination, a pair of lamp-supporting arms, a 80 pair of supports, a pair of clamps secured to said supports, respectively, and a pair of swivel members pivoted to said clamps, respectively, and to said arms on axes transverse to each other thereby to permit said 85 arms to be adjusted to various positions relative to said supports.

19. A lamp mounting comprising, in combination, a pair of independent lamp-supporting arms, a suitable support, independent 90 adjustable connections between said arms and said support, a pair of braces, and adjustable connections between said braces and said support and between said braces and said arms.

20. The combination with the handle-bar and steering-head of a cycle, of a lamp-supporting means extending forwardly from said handle-bar and steering-head, a lamp supported by said lamp-supporting means, 100 lamp-supply means supported on said lamp-supporting means at the rear of said lamp, said steering-head, handle-bar, lamp and lamp-supply means, constituting a rigid unitary structure, and means to which said unitary structure is pivoted to swing sidewise.

In testimony whereof, I have signed my name to this specification, in the presence of two subscribing witnesses.

ELLSWORTH A. HAWTHORNE.
